UNITED STATES PATENT OFFICE

ERNEST GEORGE MARKLEW, OF CALCUTTA, INDIA

FISHPLATE

Application filed October 8, 1930, Serial No. 487,162, and in India May 3, 1930.

The present invention relates to fish plates for use in railway engineering and embodies, more specifically, an improved fish plate construction by means of which expansion and contraction of the rails may be accommodated without impairing the strength and rigidity of the joints formed by the fish plates.

It is a matter of common knowledge that the expansion and contraction of rails due to changes in temperature to which they are exposed from time to time produces a highly undesirable condition which frequently results in buckling and the imposition of severe strains upon the structure associated with the rails. Over the period of a considerable number of years, indeed since the age of the wrought iron rail, attempts have been made to provide a satisfactory joint between abutting rails which accommodates such expansion and contraction without destroying the character of the joint. Great though the number of attempts have been, none has yet successfully resulted in a joint which is simple and readily formed and of sufficient strength to withstand the extreme stresses imposed thereon in service.

In approaching this problem, it must be borne in mind that the resulting joint, if of such character as to accommodate expansion and contraction between both rails, must not involve a formation on the adjacent ends of the rails other than a straight face transverse to the longitudinal axis of the rail. Any configuration other than this imposes too great a difficulty upon the repair and maintenance of the roadbed since joints must frequently be made on the road and with equipment unsuitable to the cutting of irregular profiles on the faces of rails. As a further consideration, the fish plates must be of such character that they may be readily manufactured and at small cost, further being characterized by great strength and ease of assembly.

With the foregoing in view an object of the present invention is to provide a connecting mechanism between adjacent rails, such mechanism compensating for the expansion and contraction of the rails without imposing un-

due stresses upon any portion of the rail or joint.

A further object of the invention is to provide a fish plate construction of the above character by means of which a substantially uninterrupted track surface is provided without destroying the strength and rigidity of the rail and roadbed structure.

A further object of the invention is to provide a fish plate construction of the above character by means of which the stresses imposed upon the fish plates is uniformly and equally divided between the plates to assure the proper distribution of the load carried by the joint.

A further object of the invention is to provide a fish plate construction wherein adequate provision is made against separation of the fish plates due to the gravitational load assumed thereby when a wheel is crossing the space between the adjacent ends of the connected rails. It is to be understood, of course, that this gravitational load is partly impressed upon the diverging and downwardly sloping portions of the rails, thus tending to separate the plates.

A further object of the invention is the provision of a fish plate of the above character wherein direct wheel supporting portions are formed, the amount of metal in such cooperating portions being an amount equivalent to substantially two thirds of the transverse width of the rail head.

A further object of the invention is to provide a connection of the above character wherein the fish bolts and nuts are so mounted that backing off of the nuts is prevented.

The foregoing objects are attained in the device shown herein, by providing interengaging portions between co-operating fish plates, such interengaging portions serving to cause the load which may be impressed entirely upon one plate to be carried equally by the other. It is further contemplated to provide a reinforcing securing means which adequately prevents separation of the plates due to such load.

Further objects, not specifically enumerated above, will be apparent as the invention is described in greater detail in connection

with the accompanying drawings, wherein:

Figure 1 is a view in front elevation, showing a fish plate constructed in accordance with the present invention.

Figure 2 is a plan view of the fish plate of Figure 1.

Figure 3 is a view in section, taken on line 3—3 of Figure 1, and looking in the direction of the arrows.

Figure 4 is a view in section, taken on line 4—4 of Figure 1, and looking in the direction of the arrows.

Figure 5 is a view in horizontal section, taken through a rail joint formed of two fish plates of the character shown in Figure 1, and showing the joint in such position as to accommodate the maximum contraction of the rails.

Figure 6 is a view in front elevation, showing a modified form of fish plate.

Figure 7 is a plan view of the fish plate of Figure 6.

Figure 8 is a view in section, taken on line 8—8 of Figure 6, and looking in the direction of the arrows.

Figure 9 is a view in section, taken on line 9—9 of Figure 6, and looking in the direction of the arrows.

Figure 10 is a view in longitudinal section, similar to Figure 5, showing a rail joint formed of fish plates of the character shown in Figures 6, 7, 8 and 9.

Figure 11 is a view in section, taken on line 11—11 of Figure 10 and looking in the direction of the arrows.

Figure 12 is a view in transverse section, taken through the central plane of a rail joint embodying fish plates of a slightly modified construction.

Figure 13 is a view in elevation from the inside of another form the improved fishplate may take.

Figure 14 is a plan view of Figure 13.

Figure 15 is a view in section on line 15—15 of Figure 13.

Figure 16 is a view in section on line 16—16 of Figure 13.

Figure 17 is a view in cross section of a rail showing the joint.

Figure 18 is a view in horizontal cross section of the joint on line 18—18 of Figure 17.

Figure 19 is a plan view of the joint.

Referring particularly to Figures 1 through 5, the adjacent ends of two rails are indicated at 1, these rails having bolt holes 2 formed therein in the usual fashion.

A fish plate 3 is formed with upper and lower fishing edges 4 and 5, respectively, these edges being received between the rail head and the bottom flange thereof in the usual manner. Apertures 6 are formed in one end of the fish plate 3 to cooperate with the corresponding apertures 2 of one of the rails.

The other end of plate 3 is formed with elongated slots 7 which are adapted to co-

operate with the corresponding apertures 2 in a rail to receive suitable bolts 8. These bolts are of standard construction and are used interchangeably in connection with any of the holes described herein.

In the intermediate section of the fish plate, an upwardly extending boss 9 is formed, the upper surface 10 of which is adapted to lie in the plane of the top of the rail head and thus form a continuation thereof. The boss is also extended inwardly and formed with a face 11 which lies in the central vertical plane of the rail. In mounting the above described plate 3, the boss 9 is properly spaced with respect to the adjacent circular aperture 6 to receive the rail end snugly between the edge of the shoulder 12 and the adjacent aperture. The fish plate is thus rigidly secured to the corresponding rail end and expands and contracts therewith. The other end of the plate is formed in such manner that the edge of the boss 13 is spaced a distance from the adjacent elongated aperture 7 equal to the distance between the shoulder 12 and the adjacent aperture 6.

The joint is completed by providing a co-operating fish plate 14 which is formed similarly to plate 3 and which has its elongated apertures 15 lying opposite the circular apertures 6 of the plate 3, the circular apertures 16 of plate 14 lying opposite the elongated apertures 7 of plate 3. The boss 17 of plate 14 thus is rigidly secured to the rail end to which the fish plate 3 is slidably secured and its shoulder 18 thus snugly abuts its co-operating rail end. The other shoulder 19 moves with respect to the right hand rail as viewed in Figure 5, when expansion or contraction takes place in the rails. The continuity of the rails will thus be seen to be preserved and relative movement of the adjacent rail ends will be provided for by space afforded between the shoulders and the respective rail ends.

In the construction shown in Figures 6, 7, 8, 9, 10 and 11, a fish plate 20 is formed with apertures in the manner similar to that described in connection with the plates 3 and 14. An upper boss 21 is formed on each plate and is provided with an upper surface 22 which conforms to the profile of the rail head, the boss being formed with a face 23 which lies in the vertical central plane of the rail, in the manner described in connection with the face 11. A reinforcing portion 24 is also formed on the plate and provided with downwardly depending boss 25, within which a bolt hole 26 is formed. The inner face 27 of the boss 25 lies in the plane of face 23, a longitudinal groove 28 thus being provided between the upper and lower bosses. The co-operating fish plate is similarly formed and provided with a longitudinal groove and when the joint is assembled, a key 29, indicated in dot and dash lines in Figure 8, is

inserted in the cooperating grooves to cause the fish plates to be rigidly mounted against relative movement in a vertical plane. It will thus be seen that, should one of the bosses 21 of the fish plates receive the entire gravitational load of a wheel, the key 29 will cause such load to be distributed equally between the cooperating fish plates and thus prevent injurious stresses from being impressed upon one of the plates. The bolt hole 26 is elongated, as clearly seen in Figure 6 and receives a reinforcing bolt 30 (Figures 10 and 11) which effectively prevents separation of the fish plates due to the gravitational stresses which are exerted upon the sloping faces 32 of the rails and the lower fishing edges 5 of the plates. Since the bolt holes 26 are elongated, this bolt does not prevent the relative movement of the fish plates and thus the expansion and contraction of the rails.

In the construction shown in Figure 12, the fish plates are formed with interengaging tongues and grooves which, in the form shown herein, include a longitudinal rib 33 formed upon the upwardly extending boss 34 of one of the plates which rib is adapted to be received within a longitudinal groove 35, formed within the upwardly extending boss 36 of the cooperating plate. The plate carrying the boss 36 is likewise formed with a longitudinal tongue or rib 37 which is received within a cooperating groove 38 in the plate which carries the boss 34. In this construction, the key 29 is dispensed with and the interengaging portions formed directly on the cooperating plates.

From the foregoing, it will be seen that the cooperating fish plates are effectively interconnected to insure the complete distribution of stresses between the plates and thus prevent injurious strains from being impressed upon only one plate. The plates are furthermore effectively prevented from being separated by means of the bolt 30 and as a result, a rail connection is provided, the strength of which is fully preserved, at the same time affording adequate provision for the expansion and contraction of the rails.

Referring to Figures 13 to 16 the fishplate 101 has a central upwardly projecting portion 102 which fits between the heads of the rails to be joined. In the illustration the fishplate also has a downward projection 103 which extends below the lower fishing surfaces 104 of the fishplate. The upper extension 102 is of such a width that it will not completely fill the gap between the rail ends to be joined but will allow a suitable space for expansion. This upper extension is made of two widths. The thicker part 105 may be approximately two thirds of the transverse width of the rail head to be used therewith, whilst the narrower part 106, is approximately one-third of the width of the said rail head. The part of greater width 105 has

a corresponding part 107 of similar width thereto directly below it, but the two parts 105 and 107 are separated by a gap 108. Directly below the portion 106 is another portion 109 of similar width thereto; but between 106 and 109 there is a projection 110 which is of approximately the same width as the parts 105 and 107. In effect then the central portions 102 and 103 of the fishplate constitute a portion having a width which is substantially one-third of the width of the rail head and which has thereon three projections, 105, 107 and 110 which project inwardly from this surface. When this fish plate is used with a cooperating similarly formed fish plate, the projections and grooves formed thereon interengage to permit relative axial movement without permitting relative vertical movement.

The fishplates at one end have circular holes 111 which are a close fit for the fishbolts. The holes 112 at the other ends of the fishplates are slotted holes to permit relative axial movement of the plates. The fishplate is so formed that when bolted to a rail end, the surface 113 shall make contact with the end of the rail to which that particular fishplate is rigidly connected, owing to the bolts which pass through and are a close fit in the holes 111. The expansion gap is between the surface 114 and the rail end adjacent thereto. It will be noted that the bolts which secure this second rail end to the fishplate pass through slotted holes in this fishplate and accordingly permit the fishplate to move relatively to that rail end to take up expansion contraction due to temperature variations.

A feature which will be clear from an inspection of Figure 18 is that the fish bolts 123 are mounted in such manner that their nuts 124 engage the fixed ends of the fish plates, thus eliminating movement of the fish plates below such nuts. The parts of the fish plates which move have the heads 125 of the fish bolts in contact therewith. This feature will be found advantageous since there is no tendency for the nuts to back away from the plates if there is no movement of the fishplate surface against which the nuts engage. To prevent the bolts from turning while the nuts are being tightened the fish plates above and below the slotted holes 112 are provided with fins or ribs 126 which prevent the heads 125 of the bolts from turning.

From an inspection of Figure 19, it will be seen that the above described construction provides three expansion gaps, each substantially one third of the width of the rail head. These gaps are shown at 127, 128, and 129. The wheel load therefore is carried by an amount of metal equivalent to two thirds of the width of the rail head.

While the invention has been described with specific reference to the accompanying

70

drawings, it is not to be limited, save as defined in the appended claims.

I claim as my invention:

1. A connection of the character described

1. A connection of the character described comprising cooperating opposed fish plates, means to secure one end of one of the plates rigidly to a rail, means to secure the opposite end of the other plate to another rail, means to secure the other ends of the plates to the rails with provision for relative movement with respect to the rails, wheel supporting sections on the plates, and interengaging portions on the plates to prevent relative movement therebetween vertically. 5

2. A connection of the character described comprising cooperating opposed fish plates, means to secure one end of one of the plates rigidly to a rail, means to secure the opposite end of the other plate to another rail, means to secure the other ends of the plates to the rails with provision for relative movement with respect to the rails, wheel supporting sections on the plates, and interengaging portions on the plates adjacent the wheel supporting sections to prevent relative movement therebetween vertically. 10

20

25

3. A connection of the character described comprising cooperating opposed fish plates, means to secure one end of one of the plates rigidly to a rail, means to secure the opposite end of the other plate to another rail, means to secure the other ends of the plates to the rails with provision for relative movement with respect to the rails, wheel supporting sections on the plates in the central plane thereof, and interengaging portions on the plates adjacent the wheel supporting sections to prevent relative movement therebetween vertically. 30

35

40

45

50

4. A connection of the character described comprising cooperating opposed fish plates, means to secure one end of one of the plates rigidly to a rail, means to secure the opposite end of the other plate to another rail, means to secure the other ends of the plates to the rails with provision for relative movement with respect to the rails, wheel supporting sections on the plates, a recess in one of the plates, and a projection in the other plate engaging the recess. 50

5. A connection of the character described comprising cooperating opposed fish plates, means to secure one end of one of the plates rigidly to a rail, means to secure the opposite end of the other plate to another rail, means to secure the other ends of the plates to the rails with provision for relative movement with respect to the rails, a wheel supporting boss on each plate formed with a face lying in a vertical plane parallel to the axis of the rails, a shoulder on each boss abutting the end of the rail to which the boss is securely fixed and the said shoulders of the bosses being spaced from the other rails. 70

80

85

115

5. A connection of the character described comprising cooperating opposed fish plates, means to secure one end of one of the plates rigidly to a rail, means to secure the opposite end of the other plate to another rail, means to secure the other ends of the plates to the rails with provision for relative movement with respect to the rails, wheel supporting sections on the plates, a longitudinal groove in one of the plates, and a rib on the other plate engaging the groove.

from the first bosses, and interengaging means between the bosses.

10. A connection of the character described comprising cooperating opposed fish plates, means to secure one end of one of the plates rigidly to a rail, means to secure the opposite end of the other plate to another rail, means to secure the other ends of the plates to the rails with provision for relative movement with respect to the rails, a wheel supporting boss on each plate formed with a shoulder, and a rib on each plate.

6. A connection of the character described comprising opposed fish plates, means to secure one end of one of the plates rigidly to a rail, means to secure the opposite end of the

bosses being spaced from the other rails, a lower boss on each plate below and spaced from the first bosses, interengaging means between the bosses, and a bolt securing the lower bosses together.

5 11. A connection of the character described comprising cooperating opposed fish plates, means to secure one end of one of the plates rigidly to a rail, means to secure the opposite end of the other plate to another rail, means to secure the other ends of the plates to the rails with provision for relative movement with respect to the rails, a wheel supporting boss on each plate formed with a face lying in a vertical plane parallel to the axis of the rails, one shoulder of each boss abutting the end of the rail to which the boss is securely fixed, and the other shoulder of the bosses being spaced from the other rails, a lower boss on each plate below and spaced from the first bosses, interengaging means between the bosses, an elongated aperture in one of the lower bosses, an aperture in the other boss, and a bolt in the apertures securing the bosses together.

10 12. A connection of the character described comprising cooperating opposed fish plates, means to secure the fish plates rigidly to a rail at one end, means to secure the other ends of the plates to the end of an adjacent rail with provision for relative movement with respect to the plates, wheel supporting sections on the plates, and interengaging means between the rail ends and associated with the plates to prevent relative movement thereof in a vertical plane.

This specification signed this thirteenth day of September, A. D. 1930.
